United States Patent Office

Des. 194,234
Patented Dec. 18, 1962

194,234

FLOOR SEAT

Phillip J. Ross, 8601 W. Olympic Blvd.,
Los Angeles, Calif.

Filed Feb. 23, 1962, Ser. No. 68,938

Term of patent 14 years

(Cl. D15—1)

FIG. 1 is a perspective view of a floor seat illustrating my new design;

FIG. 2 is a top plan view thereof;

FIG. 3 is a side elevational view thereof;

FIG. 4 is a front elevational view; and

FIG. 5 is a bottom view thereof.

I claim:

The ornamental design for a floor seat, as shown.
